AIR COMPRESSOR

Frederick W. Sturm, Fort Wayne, and Sherwood Hinds, Columbia City, Ind., assignors to The Wayne Pump Company, Fort Wayne, Ind., a corporation of Maryland

Application April 24, 1939, Serial No. 269,740

5 Claims. (Cl. 230—228)

This invention pertains to an air compressor. It is an object of this invention to provide an air compressor having lubricating means which is positive in operation but will not over or under oil, and wherein a constant effective oil level is maintained during operation.

Another object of the invention is to provide a compressor having oiling means wherein substantially all of the oil is used so that no part of the oil is overused.

A further object of the invention is to provide a compressor wherein the check valve, drain valve and safety valve are nested to permit ready removal, and wherein the arrangement of parts is such that the connections to the tank are maintained at a minimum.

A still further object of the invention is to provide a compressor wherein compressed air conduits are disposed to be effectively cooled, whereby the tank temperature is maintained as low as possible and substantially constant.

A different object of the invention is to provide a compressor wherein only a single open outlet is provided on the crank case and wherein the breather and gauge stick are provided as an integral construction.

A still different object of the invention is to provide a compressor wherein the operating unit or compressor bed is resiliently supported on the tank whereby the direct metal contact is eliminated and vibration of the bed is absorbed.

With these and various other objects in view, the invention may consist of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a side elevation of a compressor embodying the invention;

Figure 2 is an enlarged end elevation, partly in section, of a portion of the compressor unit embodying the invention;

Figure 3 is an end elevation of the compressor illustrated in Figure 1, the same being shown as looking toward the right as viewed in said figure;

Figure 4 is an enlarged sectional elevation of one end of the compressor unit showing a portion of the oiling arrangement thereof;

Figure 5 is an enlarged sectional elevation of the valve nest embodying the invention and showing its connection to the storage tank;

Figure 6 is an enlarged sectional elevation of a valve assembly for the compressor head;

Figure 7 is an enlarged top plan view of the valve assembly illustrated in Figure 6;

Figure 8 is an enlarged top plan view of the valve seat for the assembly illustrated in Figure 6;

Figure 9 is an enlarged top plan view of the valve retainer of the valve assembly illustrated in Figure 6;

Figure 10 is an enlarged top plan view of a valve disc of the valve assembly shown in Figure 6;

Figure 11 is an enlarged top plan view of the valve retainer spring for the valve assembly illustrated in Figure 6.

In the compressor illustrated, the tank 20 is provided with the spaced supports 22 and the normally closed manual relief valve 24. The tank 20 is provided with the spaced supporting members 26 shown of substantially Z-bar construction, being fixedly secured to said tank and forming a support for the resilient cushions 28 which may be of live rubber or other suitable material on which the compressor bed 30 is supported, being secured thereto as at 32.

The compressor 34 is secured to the compressor bed by means of the pedestal 36, said compressor, in the form illustrated, comprising the low pressure cylinder 38 and the high pressure cylinder 40 provided with cooling veins 42, the cylinder block being provided with the crank case 44 secured as at 46 to the oil pan or basin 48. The cylinders are closed by means of the cylinder head 50 secured thereto as at 52, the atmosphere inlet passage 54 of the low pressure cylinder being provided with the inlet 56 having the muffler 58 thereon. The cylinder head is provided on the inlet side with the valve assembly 60 of a form as will be described with respect to Figures 6 to 11 inclusive.

The low pressure cylinder is provided with a low pressure piston 62, and the high pressure cylinder is provided with a high pressure piston 64, said pistons being connected through the wrist pins 66 and 68 to the piston rods 70 and 72, said piston rods being journaled through suitable bearings as indicated at 74, for the high pressure cylinder, to the crank shaft 76. The crank shaft 50 is supported at one end on the roller bearing 78, the outer race of said bearing being shown as supported in the cap or end closure plate 80 secured to the crank case as at 82, the inner race ring of the bearing being fixedly secured to the crank shaft as at 84. The opposite end of the

crank shaft is provided with similar roller bearings (not shown), passes through a suitable journal box 86, and is provided with the flywheel 88 fixedly secured to rotate with the shaft as at 80, the securing means and key therefor being generally indicated as at 92. The flywheel is shown as of the multiple V type for accommodating the belts 94, adapted to be rotated by means of the pulley 96 provided on the rotating shaft of the operating motor 98. The flywheel 88 is provided with the vanes 100 so disposed that when the flywheel is rotated air will be blown toward the cylinders by the action of said vanes.

The piston rods 10 and 72 are provided with the downwardly extending dip pins or depending members 102 adapted to pass through or dip into the transverse trough 104, said trough being connected to the longitudinal troughs 106 provided in the oil pan 48, it being understood, of course, that a transverse trough 104 is provided for both the high and low pressure piston rods.

The crank shaft is provided with the disc 108 disposed at one end thereof and adapted to rotate in the recess 110, the disc being shown as secured between the inner race of the roller bearing assembly and the crank shaft, and being flattened on the sides thereof as at 112 to facilitate entry into the crank case through the apertures 114 normally closed by the cover plate 80, the shape also aiding in throwing the lubricant from the disc. The disc is adapted to dip into the oil provided in the lower portion of the oil pan, the level thereof being illustrated as at 116, the lubricant being picked up by the disc 108 and thrown by centrifugal force against the walls 118 of the crank case and running down into the trough 106, and consequently the troughs 104, the action of the disc and the pins 102 serving to vaporize the oil to permit ready lubrication of the bearings. The crank case is provided with the opening for receiving the breather pipe 120 which is made removable and is provided with the oil gauge 122 adapted to extend to the bottom of the oil pan.

The outlet valve 124 of the low pressure cylinder is of similar construction to the inlet valve 60, and communicates with the outlet manifold 126 connected to the fitting 128 which in turn is connected to the tubing 130. The tubing 130 extends downwardly and is disposed in a plane between the flywheel and the cylinders in order to be readily cooled from the air passing from the vanes 100. Said tubing is shown as being formed in a single loop, the opposite end thereof being connected to the fitting 132 connected to the inlet manifold 134 of the high pressure cylinder. The inlet manifold 134 is connected to the high pressure cylinder through the valve assembly 136 of similar construction to the valve assembly 60, and the outlet valve therefrom (not shown) is likewise of similar construction. The manifold of the outlet valve of the high pressure cylinder is connected to the fitting 138 which in turn is connected to the tubing 140, which in turn is disposed in the plane of and within the loop formed by the tubing 130 in order to be cooled. The tubing 140 preferably is looped a plurality of times and is connected to the valve nest 142 as at 144.

The tubing 140 is connected to the passage 146 having the valve seat 148 therein on which the valve 150 is seated, said valve being urged toward closed position by means of the outer spring 152 and the inner spring 154, the inner spring being a stiff spring effective to prevent noise of the

valve, and preferably not being effective in operation against the valve until after predetermined operation of the outer spring, said springs being retained by means of the retaining member 156 threaded to the valve nest. The passage 146 communicates through said valve to the passage 158 to which the safety valve 160 has access, said safety valve including the housing member 162, the guide enclosure member 164, the valve stem 166, and the normally closed valve 168 urged towards closed position on its seat 170 by means of the spring 172, the valve when in open position due to excess pressure, permitting communication with the atmosphere.

15 The passage 158 likewise communicates with the passage 174, which in turn is connected to the pipe 176 suitably secured as at 178 to the fitting 180 communicating with the tank, the fitting being welded or otherwise secured to the tank as at 182. The passage 174 likewise communicates through the fitting 184 to the pressure control mechanism 186 of the automatic control device 188, said device being of a well known make in which an electrical switch is mounted 20 therein for controlling operation of the motor 98. The usual pressure gauge 189 is also provided on the nest 142 communicating with the tank.

When the pressure reaches a predetermined 30 point, the pressure control device 186 is operated to open the switch and stop the motor. When the pressure in the tank falls to a predetermined amount, the pressure control device 186 permits the switch to be closed to start the motor. When 35 the switch is moved to open position the normally closed valve 190 is operated to form a connection between the exhaust pipe 191 and the pipe 192, one end of which is connected to the said valve through the fitting 194, the other end 40 of which is connected to the fitting 196 which, in turn, is connected to the conduit 146, the opening of the valve 190 causing pressure in the compressor to be relieved as the tubing 140 is thus vented to atmosphere.

45 In order to provide a means for expelling moisture due to condensation in the tank, the pipe 198 extends from a low point in the tank to the manually controlled needle valve 200, the control means therefor being indicated as at 202, the pipe 198 being disposed within the pipe 176. The valve 200 is connected to the piping 204 which is likewise connected to the exhaust pipe 191. It will thus be seen that when pressure is in the tank it is only necessary to open the valve 200 50 and the compressed air in said tank will cause the liquid therein to move upwardly in the pipe 198 and to be expelled through the pipe 191.

The valve mechanism 60, and the similar valve mechanisms for the cylinder head of the compressor, consist essentially of a valve seat member 206 threaded as at 208 to provide securing means therefor. The valve seat is provided with the radially disposed elongated openings 210 disposed axially of the seat member, and surrounding said openings, the marginal projecting flanges 212 and 214 are disposed, forming seat members for the valve discs 216, said members being disposed in the recess 217 within the seat member formed by a cylindrical portion or skirt 70 on which the threads 208 are disposed. The valve disc 216 is provided with the central aperture 218 and the flattened side portions 220, and said valve disc is normally urged toward closed position by means of the spring 222 disposed between the valve disc and the valve retainer 224.

The valve retainer 224 is provided with the plurality of apertures 226, and said retainer is adapted to be received and seated against the seat 228 of the valve seat 206, being retained therein by means of the valve retainer spring 230 received when in operative position in the recess 232. The retainer spring is provided with the inwardly extending flanges 234 which may be readily engaged and moved toward each other for contracting the spring to permit ready seating within the recess 232 and ready release therefrom whereby the valve assembly may be easily assembled and disassembled. This type of assembly may be used as an inlet or outlet valve merely by installing in reverse direction, and it is understood that this type of assembly may be used for any stage.

It is to be understood that we do not wish to be limited by the exact embodiments of the device shown, which are merely by way of illustration and not limitation as various and other forms of the device will of course be apparent to those skilled in the art without departing from the spirit of the invention or the scope of the claims.

We claim:

1. In a compressor, the combination of a cylinder, a piston in said cylinder, an inlet and an outlet valve assembly in said cylinder, each of said valve assemblies being interchangeable but oppositely arranged, said assemblies including a valve seat comprising a member having securing means and a recess, elongated openings disposed radially and axially of said seat, concentric members disposed on each side of said openings forming valve seats, a valve disc having flattened side portions and a central aperture, said disc being adapted to engage said seats to close communication through said openings, a seat spaced from said disc in said recess, an apertured retaining member disposed on said last named seat, means for fixing said retaining member to said seat, said means including a groove spaced from said seat, a resilient member adapted to be sprung into said groove, said resilient member having spaced inwardly extending flanges at the ends thereof adapted to be moved toward each other to contract said member for insertion or removal into the groove, resilient means disposed between said disc and retaining member normally urging said disc to seated position, a crank case and oil pan, a crank shaft in said crank case, a piston rod connecting said piston and crank shaft, an oil trough in said oil pan disposed below said rod, a second trough communicating with said first named trough and disposed along the side of said oil pan, means associated with said rod adapted to splash oil in one of said troughs, means for maintaining oil in said troughs including a disc disposed on and rotatable with said crank shaft, said disc extending into the oil pan below said troughs, said compressor having a flywheel, means for driving said compressor connected to said flywheel, a storage tank, a connection from said compressor to said tank including a pipe, said connection including a housing member, a valve urged toward closed position against the compressed fluid supplied by the compressor, a safety valve between said valve and tank communicating with atmosphere and set for a predetermined pressure, an inlet connection from said housing to said tank, a normally closed pressure operated valve associated with said housing and operated after a predetermined pressure exists in said tank, and a connection in said housing between said first named valve and said compressor controlled by said last named valve.
2. In a compressor, the combination of a cylinder, a piston in said cylinder, an inlet and an outlet valve assembly in said cylinder, each of said valve assemblies being interchangeable but oppositely arranged, said assemblies including a valve seat comprising a member having securing means and a recess, elongated openings disposed radially and axially of said seat, concentric members disposed on each side of said openings forming valve seats, a valve disc having flattened side portions and a central aperture, said disc being adapted to engage said seats to close communication through said openings, a seat spaced from said disc in said recess, an apertured retaining member disposed on said last named seat, means for fixing said retaining member to said seat, said means including a groove spaced from said seat, a resilient member adapted to be sprung into said groove, said resilient member having spaced inwardly extending flanges at the ends thereof adapted to be moved toward each other to contract said member for insertion or removal into the groove, resilient means disposed between said disc and retaining member normally urging said disc to seated position, a crank case and oil pan, a crank shaft in said crank case, a piston rod connecting said piston and crank shaft, an oil trough in said oil pan disposed below said rod, a second trough communicating with said first named trough and disposed along the side of said oil pan, means associated with said rod adapted to splash oil in one of said troughs, means for maintaining oil in said troughs including a disc disposed on and rotatable with said crank shaft, said disc extending into the oil pan below said troughs, said compressor having a flywheel, means for driving said compressor connected to said flywheel, a storage tank, a connection from said compressor to said tank including a pipe, said connection including a housing member, a valve urged toward closed position against the compressed fluid supplied by the compressor, a safety valve between said valve and tank communicating with atmosphere and set for a predetermined pressure, an inlet connection from said housing to said tank, a normally closed pressure operated valve associated with said housing and operated after a predetermined pressure exists in said tank, and a connection in said housing between said first named valve and said compressor controlled by said last named valve.
3. In a compressor, the combination of a cylinder, a piston in said cylinder, an inlet and an outlet valve assembly in said cylinder, each of said valve assemblies being interchangeable but oppositely arranged, said assemblies including a valve seat comprising a member having securing means and a recess, elongated openings disposed radially and axially of said seat, concentric members disposed on each side of said openings forming valve seats, a valve disc having flattened side portions and a central aperture, said disc being adapted to engage said seats to close communication through said openings, a seat spaced from said disc in said recess, an apertured retaining member disposed on said last named seat, means for fixing said retaining member to said seat, said means including a groove spaced from said seat, a resilient member adapted to be sprung into said groove, said resilient member having spaced inwardly extending flanges at the ends thereof adapted to be moved toward each other to contract said member for insertion or removal into the groove, resilient means disposed between said disc and retaining member normally urging said disc to seated position, a crank case and oil pan, a crank shaft in said crank case, a piston rod connecting said piston and crank shaft, an oil trough in said oil pan disposed below said rod, a second trough communicating with said first named trough and disposed along the side of said oil pan, means associated with said rod adapted to splash oil in one of said troughs, means for maintaining oil in said troughs including a disc disposed on and rotatable with said crank shaft, said disc extending into the oil pan below said troughs, said compressor having a flywheel, means for driving said compressor connected to said flywheel, a storage tank, a connection from said compressor to said tank including a pipe, said connection including a housing member, a valve urged toward closed position against the compressed fluid supplied by the compressor, a safety valve between said valve and tank communicating with atmosphere and set for a predetermined pressure, an inlet connection from said housing to said tank, a normally closed pressure operated valve associated with said housing and operated after a predetermined pressure exists in said tank, and a connection in said housing between said first named valve and said compressor controlled by said last named valve.

to contract said member for insertion or removal into the groove, resilient means disposed between said disc and retaining member normally urging said disc to seated position, a crank case and oil pan, a crank shaft in said crank case, a piston rod connecting said piston and crank shaft, an oil trough in said oil pan disposed below said rod, a second trough communicating with said first named trough and disposed along the side of said oil pan, means associated with said rod adapted to splash oil in one of said troughs, means for maintaining oil in said troughs, means for driving said compressor, a storage tank, a connection from said compressor to said tank including a pipe, said connection including a housing member, a valve urged toward closed position against the compressed fluid supplied by the compressor, a safety valve between said valve and tank communicating with atmosphere and set for a predetermined pressure, an inlet connection from said housing to said tank, a normally closed pressure operated valve associated with said housing and operated after a predetermined pressure exists in said tank, and a connection in said housing between said first named valve and said compressor controlled by said last named valve.

4. In a compressor, the combination of a cylinder, a piston in said cylinder, an inlet and an outlet valve assembly in said cylinder, each of said valve assemblies being interchangeable but oppositely arranged, said assemblies including a valve seat comprising a member having securing means and a recess, elongated openings disposed radially and axially of said seat, concentric members disposed on each side of said openings forming valve seats, a valve disc having flattened side portions and a central aperture, said disc being adapted to engage said seats to close communication through said openings, a seat spaced from said disc in said recess, an apertured retaining member disposed on said last named seat, means for fixing said retaining member to said seat, said means including a groove spaced from said seat, a resilient member adapted to be sprung into said groove, said resilient member having spaced inwardly extending flanges at the ends thereof adapted to be moved toward each other to contract said member for insertion or removal into the groove, resilient means disposed between said disc and retaining member normally urging said

disc to seated position, a crank case and oil pan, a crank shaft in said crank case, a piston rod connecting said piston and crank shaft, an oil trough in said oil pan disposed below said rod, a second trough communicating with said first named trough and disposed along the side of said oil pan, means associated with said rod adapted to splash oil in one of said troughs, means for maintaining oil in said troughs, means for driving said compressor, a storage tank, a connection from said compressor to said tank including a pipe, said connection including a housing member, a valve urged toward closed position against the compressed fluid supplied by the compressor, an inlet connection from said housing to said tank, a normally closed pressure operated valve associated with said housing and operated after a predetermined pressure exists in said tank, and a connection in said housing between said first named valve and said compressor controlled by said last named valve.

5. In a valve nest, the combination of a valve seat comprising a skirt having securing means externally thereof and a recess formed therein, one of the ends of said skirt being open, the opposite end of said skirt being provided with a web having elongated openings therein, said openings being disposed radially and axially of said seat, marginal means surrounding said openings and projecting within said skirt, said marginal means forming valve seats, a retaining shoulder spaced from said web, an apertured retaining member engaging said shoulder, means for fixing said retaining member against said retaining shoulder, said last named means including a groove provided in said skirt and spaced from said retaining shoulder a distance substantially equal to the thickness of said retaining member, readily movable resilient retaining means adapted to be sprung into said groove, a valve disc having flattened side portions and a substantially central aperture for permitting passage around and through said disc when said disc is spaced from said seats, said disc being adapted to engage said seats to close communication through said openings, and resilient means disposed between said valve disc and retaining member urging said valve disc toward closed position.

CERTIFICATE OF CORRECTION.

Patent No. 2,267,479.

December 23, 1941.

FREDERICK W. STURM, ET AL.

It is hereby certified that error appears in the printed specification of the above numbered patent requiring correction as follows: Page 4, second column, line 38-39, claim 5, for "movable" read --removable--; and that the said Letters Patent should be read with this correction therein that the same may conform to the record of the case in the Patent Office.

Signed and sealed this 17th day of March, A. D. 1942.

Henry Van Arsdale,
Acting Commissioner of Patents.
